ARTICLE SORTING APPARATUS

William H. Wilcox, Stockton, Calif., assignor to
 California Cedar Products Company, a corpora-
 tion of California

Application October 17, 1938, Serial No. 235,476

14 Claims. (Cl. 214—11)

This invention is directed in general to an article sorting device, and in particular is directed to apparatus for assorting articles, and especially pencil slats, according to the physical characteristics thereof. In the manufacture of pencil slats, the slats are graded for size, grain, color, defects, etc.; such grading now being done by persons who grasp a stack of slats from a conveyor and then manually assort such slats into different stacks or bins according to the grade thereof. This manner of grading is inefficient and substantially slows down the production flow of a pencil slat manufacturing plant due to the fact that each and every slat must be picked up and handled by the person grading the same.

It is therefore the principal object of this invention to provide a method of and apparatus for sorting or grading articles wherein the articles are presented on a support, such as a conveyor, before a person for visual inspection, are then identified by means manually actuated by the person according to grade, and are subsequently discharged from the support in segregated grades by mechanism placed in operation by said identifying means; all without any person manually removing the articles from the support. By employing such method and apparatus, effective grading is accomplished by a minimum of time.

An additional object of the invention is to provide article sorting apparatus as above wherein potential holding condensers are arranged in corresponding relation to articles on the support, and including means whereby any one of the condensers may be charged, by a person inspecting the articles, with a certain potential; there being mechanism actuated by said potential to subsequently discharge the corresponding article from the support.

A further object of the invention is the inclusion of means whereby a person may effect a discharge of the potential in any one of the condensers in the event that a grading error is made.

Another object of the invention is to provide article sorting apparatus, as above, wherein the articles are supported on a moving conveyor and wherein the condensers are supported for corresponding movement adjacent the articles; the person inspecting the articles being provided with means to selectively impart a potential of any one of several intensities to any one condenser and according to that potential intensity predetermined to represent a certain grade, and the apparatus including separated mechanisms mounted adjacent the conveyor and each arranged to

be placed in operation only by a condenser having a certain one of said potential charges.

A further object of the invention is to produce a relatively simple device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Figure 1 is a somewhat diagrammatic side elevation of the apparatus.

Figure 2 is an enlarged, fragmentary side elevation of the article conveyor and associated mechanism including certain of the condensers and wiping contacts.

Figure 3 is an enlarged cross section on line 3—3 of Fig. 1.

Figure 4 is a perspective view of the operator's glove and including the charged thimbles.

Figure 5 is a diagram of one of the circuits employed with the apparatus.

Referring now more particularly to the characters of reference on the drawings, the apparatus comprises a relatively long horizontal table 1 supported by suitable means above a frame including horizontal frame members 2 and legs 3. A pair of laterally spaced endless belts 4 extend horizontally from end to end of the apparatus; these belts being supported at their ends on and driven by pulleys 5 mounted on cross shafts 6 in connection with frame members 2. The upper reaches of the belts 4 run on top of table 1 in spaced, parallel relation and adjacent the side edges of said table. One of the shafts 6 is driven, in any suitable manner, to effect like movement of both belts 4 in the direction indicated by the arrows in Fig. 1. The pencil slats S to be assorted or graded are fed onto the receiving end of the upper reaches of the moving belts 4 in flat, transversely extending position; the slats being spaced apart slightly along adjacent edges. This feeding of the slats onto the belts is accomplished by means of any desired mechanism. The table 1 is of less width than the length of the slats S to be sorted and the slats when disposed on the belts project laterally beyond one side of the table in the manner shown in Fig. 3 and for the purpose 50 hereinafter described.

An endless chain 7 is carried at the ends by sprockets 8 journaled in connection with frame member 2; the chain being horizontal and disposed parallel with belts 4 but to one side of 55

table 1 and with the upper reach of the chain traveling in a horizontal plane below the plane of said table. Chain 7 is driven at the same speed as belts 4 by a sprocket and chain drive, indicated generally at 9, which extends between one of the shafts 6 and the shaft for the adjacent sprocket 8.

Every other link of chain 7 is an attachment link and an outwardly extending block 10 of dielectric material is fixed thereon; such blocks 10 being elongated and mounted centrally of their ends transversely of the chain. The slats S are of a width greater than the combined width of any two of the blocks as mounted on the chain. These blocks 10 are provided with metallic upper 15 faces 11 whose longitudinal edge portions are turned down and pinched in as at 12 to prevent escape of said faces. These faces each include a contact finger 13 which projects upwardly from a point adjacent the inner end of each block, this 20 being the end nearest the table.

The blocks are each formed with a longitudinally extending bore therethrough and a fixed condenser 14 of the cylindrical type is mounted in such bore; one end lead 15 of the condenser 25 connecting with the corresponding face 11 as shown in Fig. 2, while the lead 16 at the other end is grounded to the corresponding attachment link of the chain as shown in Fig. 3.

A longitudinal row of open top bins 16 extends 30 from a point intermediate the ends of the conveyor belts 4 to adjacent the discharge end thereof; each of these bins being for the reception of slats of a certain grade and which are discharged from the belt conveyor, at the proper time, in the 35 manner hereinafter described. These bins are disposed below and laterally out from the table 1 and on the side opposite from chain 7.

A plurality of electrically actuated slat "kick off" mechanisms, indicated generally at 17, are 40 mounted on a frame 18 above the table; each mechanism being positioned and arranged to discharge slats laterally off the belt conveyor and into one of the bins. Each of these mechanisms comprises a relatively long kicker lever 45 19 pivoted at 20 on frame 18 for swinging movement in a plane transversely of the conveyor. The pivot point 20 is disposed substantially vertically above the end portion of the slats which project beyond the edge of the table; the lever 50 normally being held on a downward and outward slope, and out of the path of the projecting slat ends, by means of a tension spring 21. Suitable stop means 22 for the lever is included 55 in order to limit movement thereof under the influence of the spring. An electromagnet 23 is mounted on frame 18 with its core in a plane transversely of the conveyor and in position when actuated to act on lever 19 at a point close to but below pivot 20 and to swing or snap the lever 60 toward the table. With such movement, the lever strikes the end of any slat which may then be positioned in its path and throws or "kicks" the slat laterally off the conveyor into the corresponding bin 16. The edge of the table adjacent 65 each lever is provided with a resilient cushion 24 against which the lever engages at the end of its stroke; the cushion absorbing the shock and preventing undue noise.

A wiping contact 25 is mounted on the table 70 in insulated relation thereto immediately below each of the mechanisms 17; these wiping contacts engaging each of the upstanding contact fingers 13 as the latter pass thereby. Beyond the mechanisms 17 and adjacent the end of the 75 conveyor, another wiping contact 26 is mounted

for engagement with contact fingers 13; this contact 26 being grounded with the metal table and frame.

A closed receptacle 27 is mounted beneath the table adjacent each mechanism 17 and houses an 5 electrical unit which serves to actuate such mechanism in the manner hereinafter described. The electrical units are identical and each comprises a circuit—as shown in Fig. 5—including a thyatron discharge tube 28 or other similar electronic relay. The grid 29 of this tube is connected by wire 30 with one end of a limiting resistor 31; the other end of such resistor being connected, as at 32, with one end of another resistor 33 whose remaining terminal is connected 15 with a wire 34 grounded at 35. A lead in wire 36 is connected to the corresponding wiper contact 25 and leads to the connection 32 between condensers 31 and 33.

The 2½ volt current for the filament 37 of the 20 tube is supplied by wires 38 from the low voltage secondary winding 39 of a power transformer 40 whose input or primary winding leads 41 are connected with 110 v. A. C. lines 42. The plate 43 of the tube is connected by wire 44 with one terminal of the electromagnet 23 of the corresponding mechanism 17; the other terminal of the electromagnet being connected by wire 45 with one lead of the high voltage (440 volt) secondary winding 46 of transformer 40. 30

The other lead from the secondary winding 46 is connected by a wire 47 to one end of a bias resistor 48 (30,000 ohms) whose other end is connected to wire 49 which is tapped into secondary winding 46 intermediate its ends. Another wire 50 leads from wire 49 to the initial turn of the low voltage secondary winding 39. From a point intermediate the ends of resistor 48, a lead 51 is tapped off and extends to connection with wire 34. A fixed condenser 52 is wired between 40 wires 44 and 45 ahead of the electromagnet and this condenser kills any inductive kick back in the circuit and which might otherwise damage the insulation in the coil.

Each of the circuits of the four electrical units 45 is normally biased, and the circuits are set so that the tube 28 in each becomes unbalanced upon a different potential charge flowing into the circuit through wire 36. The circuit of the unit 50 for the mechanism 17 nearest the receiving end of the conveyor requiring a predetermined potential charge to actuate said circuit; the circuits of the units for the remaining mechanisms 17 each requiring a less potential than the circuit of the unit for the next preceding mechanism 17. 55

When the tube of any one circuit is unbalanced, an instantaneous current flows through wires 44 and 45 of such circuit and actuates the magnet which in turn swings the corresponding lever in a slat discharging direction. The circuit 60 which I have described above is preferred although other similar circuits may be employed.

Operation

In operation of the apparatus, an operator 65 takes a position alongside the belt conveyor ahead of the mechanism 17; such operator being trained to accomplish a rapid visual determination of the several grades of the slats passing on said conveyor. In the present embodiment, the 70 apparatus is designed to segregate pencil slats into five grades; four grades being discharged into corresponding bins 16, and the fifth grade permitted to pass to the discharge end of the conveyor. The four grades to be discharged 75

from the conveyor into the bins correspond—by predetermination—with the different potential charges required to actuate the circuits and mechanisms 17.

5. The operator wears a dielectric glove 53 on one hand; such glove at the finger tips having metallic thimbles 54 fitted thereon. A five wire electric cord 55 leads from a conventional power supply unit 56 which receives current from 110 volt 10 A. C. wires 57. The thimbles 54 of four fingers of the glove are each charged through one of the wires of cord 55 from the power supply unit and with potentials proportionate to the potentials required to actuate the four electrical units 15 and mechanisms 17, and which potentials also correspond to the four slat grades. For example, the four thimbles will be charged—in consecutive order—with potentials of 10, 20, 30 and 40 volts; all of one polarity and preferably positive. The 20 remaining thimble, preferably the one on the thumb, carries a negative or ground potential; the wire for said thumb thimble being grounded as at G.

As the slats pass in view of the operator they 25 are inspected and all of the so-called fifth grade are permitted to pass. However, when a slat of one of the four grades appears, the operator touches the metal face 11 of a block 10, which is alined with such slat, with the charged thimble 30 having the potential which corresponds to the grade of such slat. This charges the condenser in such block with a like potential. The block and its charged condenser move along with chain 7 at the same speed as the conveyor, and the contact finger 13 of the block engages each wiping contact 25 as it passes. When the finger 13 engages the wiping contact included in the circuit which is set to be actuated by a potential of the intensity which the condenser of such block 40 is carrying, such circuit imparts a current instantaneously to the electromagnet, the lever 19 of which in turn snaps toward and strikes the end of the selected slat and discharges the same laterally off the conveyor into the proper bin 45 16. If the condenser in the block should retain any of the charge, this is grounded out by wiping contact 26 which is disposed beyond the mechanisms 17.

By means of the apparatus and method described, slats visually identified for segregation by grade, can be manually identified by the operator charging an alined block supported condenser with a corresponding potential charge, and thereafter the apparatus automatically segregates the 55 slats. The grading and segregating according to grade of articles, such as pencil slats, can thus be accomplished more rapidly than when done directly by hand, more efficiently, and with a minimum of error. Should an operator charge one 60 condenser by error, the glove thimble of negative or ground potential is touched to the corresponding plate and the original charge grounded out.

From the foregoing description it will be readily seen that I have produced such a device as 65 substantially fulfills the objects of the invention as set forth herein.

While this specification sets forth in detail the present and preferred construction of the device, still in practice such deviations from such detail 70 may be resorted to as do not form a departure from the spirit of the invention, as defined by the appended claims.

Having thus described my invention, what I 75 claim as new and useful and desire to secure by Letters Patent is:

1. Article sorting apparatus comprising a movable support adapted to receive a plurality of articles thereon for visual inspection, a plurality of condensers disposed adjacent the support and movable therewith in unchanging relative position, one condenser corresponding to each article, manually actuated means to charge any one condenser with a given potential, an article discharging mechanism mounted adjacent the support, the support being adapted to move relative thereto, and means placed in operation by the potential in said one condenser to actuate said discharge mechanism when the article corresponding to said condenser is moved to a position for discharge by said mechanism. 10 15

2. Article sorting apparatus comprising a conveyor adapted to receive a plurality of articles for visual inspection, a plurality of condensers disposed adjacent the conveyor and moving therewith in unchanging relative position, one condenser corresponding to each article, a plurality of article discharging mechanisms disposed adjacent the conveyor in spaced relation, separate electrical means arranged to actuate each such mechanism, said means each being placed in operation by a different potential, means to successively connect the individual condensers in circuit with said electrical means when the condensers reach points in their travel such that the corresponding articles are then in position to be 20 discharged by the mechanisms, and manually actuated means to charge any condenser with any one of such different potentials selectively. 25 30

3. An apparatus as in claim 2 in which each separate electrical means includes a circuit having a normally balanced electronic relay interposed therein; the circuit initially connected with any one charged condenser being set to unbalance and pass an actuating current to the corresponding mechanism upon a predetermined potential being received from said condenser; the circuits of the following electrical means each requiring a less potential to unbalance the same than the circuit of the next preceding electrical means. 40 45

4. Article sorting apparatus including a horizontal conveyor adapted to receive a row of articles in single file order for visual inspection, a plurality of condensers disposed adjacent the conveyor and moving therewith in unchanging relative position, one condenser being alined with each article, an exposed charging plate mounted with each condenser, a plurality of article discharging mechanisms disposed adjacent the conveyor in spaced relation, separate electrical means arranged to actuate each such mechanisms, said means each being placed in operation by a different potential, means to successively connect the individual condensers in circuit with said electrical means when the condensers reach points in their travel such that the corresponding articles are then in position to be discharged by the mechanisms, and manually actuated means adapted to touch any one of said condenser charging plates and to charge the corresponding condenser with any one of such different potentials. 50 55 60

5. A device as in claim 4 in which said manually actuated means includes a glove adapted to be worn by a person visually inspecting the articles; said glove including a plurality of metallic thimbles on the ends of certain fingers, a power supply unit, and separate wires connecting such unit and each thimble and charging each with one of such different potentials. 70

6. A device as in claim 4 in which said manu- 75

- ally actuated means includes a glove adapted to be worn by a person visually inspecting the articles; said glove including a plurality of metallic thimbles on the ends of the fingers, a power supply unit, and separate wires connecting such unit with each thimble, a plurality of the thimbles being charged with such different potentials but all of like polarity, while another thimble carries a potential of opposed polarity.
10. Article sorting apparatus including a conveyor adapted to receive a row of articles in single file order for inspection, a mechanism mounted adjacent the conveyor and arranged to discharge individual articles from the conveyor, said mechanism including an electromagnet, normally inactive electrical means to energize said electromagnet, a plurality of condensers disposed adjacent the conveyor and moving therewith in unchanging relative position, one condenser corresponding to each article, means to charge any one of said condensers with a potential of sufficient intensity to actuate said electrical means, and means to connect each of said condensers with said electrical means when each of the condensers reaches a point in its travel such that the corresponding article is then in position to be discharged from the conveyor by said mechanism.
8. Article sorting apparatus comprising a conveyor adapted to receive a plurality of articles thereon for visual inspection, manually actuated means to identify the passing articles with identifying media corresponding to certain grades, and other means placed in operation by said identifying media to segregate said articles according to such grades; said manually actuated means including a plurality of condensers disposed adjacent the conveyor and moving therewith in unchanging relative position.
9. Article sorting apparatus comprising a conveyor adapted to receive a plurality of articles thereon, means to identify passing articles with identifying media, and other means placed in operation by said identifying media to segregate the identified articles; said first named means including a plurality of electric potential holding elements associated with the conveyor and moving in predetermined relation thereto.
10. Apparatus as in claim 8 in which said manually actuated means includes a glove adapted to be worn by a person visually inspecting the articles, a plurality of metallic thimbles on the ends

of certain fingers of the glove, a power supply unit and wires connected between the power supply unit and thimbles and arranged to supply a pre-determined potential to each thereof; each condenser having an exposed charging member.

11. An apparatus as in claim 8 in which the conveyor is of the endless belt type; the condensers being mounted on an endless chain mounted for travel in the same direction and at the same speed as the conveyor belt, the upper reaches of the conveyor and chain being disposed parallel to each other and in relatively close proximity to each other.

12. An apparatus as in claim 8 in which the conveyor is of the endless belt type; the condensers being mounted on an endless chain mounted for travel in the same direction and at the same speed as the conveyor belt, the upper reach of the conveyor being substantially horizontal, and the corresponding reach of the chain being disposed parallel with, laterally out, and offset downwardly relative to said upper reach of the conveyor.

13. Article sorting apparatus comprising a conveyor adapted to receive a plurality of articles for visual inspection, a plurality of condensers disposed adjacent the conveyor and moving therewith in unchanging relative position, one condenser corresponding to each article, manually actuated means to charge any condenser with a potential, an article discharging mechanism disposed adjacent the conveyor, electrical means arranged to be placed in operation by said potential and to actuate such mechanism, and means to successively connect the individual condensers in circuit with said electrical means when the condensers reach a point in their travel such that the corresponding article is then in position to be discharged by the mechanism; said last named means including an exposed metallic charging plate electrically connected with each condenser, a contact finger projecting from the charging plate, and a wiping contact arranged in circuit with said electrical means and mounted for engagement with the contact finger.

14. Apparatus as in claim 13 including another wiping contact mounted beyond said first named wiping contact and arranged to ground out any potential which may remain in any one previously charged condenser.

WILLIAM H. WILCOX.
